CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken line showing of the oblong-shaped unshaded region within the shaded area forms no part of the claimed design. The broken lines depicting the remainder of the shoe show features that form no part of the claimed design.
